ELECTRO-MECHANICAL SHAFT POSITIONING DEVICE

Charles L. Cohen and Donal F. Luse, Jr., Hyattsville, Md., assignors to ACF Industries, Incorporated, New York, N.Y., a corporation of New Jersey
Filed Mar. 6, 1959, Ser. No. 797,804
2 Claims. (Cl. 74—10.2)

This invention relates to electro-mechanical shaft positioning devices and, more particularly, to devices operable either automatically or manually for rapidly tuning radio apparatus and the like to selected positions corresponding to selected frequencies.

An object of the invention is to provide an electro-mechanical shaft positioning device operable either automatically or manually in either direction for rapidly and accurately tuning a radio apparatus or the like to pre-selected positions or frequencies.

Another object of the invention is to provide an electro-mechanical shaft positioning device embodying means for pre-selecting the shaft position or frequencies to be obtained during operation of the device.

Another object of the invention is to provide an electro-mechanical shaft positioning device embodying means for pre-selecting the shaft positions or frequencies to be obtained during operation of the device.

A further object of the invention is to provide a tuning device in which a tuning shaft is rotatable in either direction by an electric motor connected thereto through a link and lever drive mechanism, and a friction clutch interposed between said motor and mechanism.

Another object of the invention is to provide a tuning device embodying a pair of adjustable stop members to limit movement of the drive mechanism in either direction.

Another object of the invention is to provide a tuning device which is relatively simple and inexpensive to manufacture and reliable in use.

The invention embodies other novel features, details of construction and arrangement of parts which are hereinafter set forth in the specification and claims and illustrated in the accompanying drawings, forming part thereof, wherein:

FIG. 1 is a front elevation illustrating an electro-mechanical shaft positioning device embodying features of the invention.

FIG. 2 is a side elevation showing the device.

FIG. 3 is a section taken along the line 3—3 of FIG. 1.

Referring now to the drawings for a better understanding of the invention, the electro-mechanical shaft positioning device is shown as comprising a housing 5 having a tuning shaft 6 journaled thereon for turning a variable radio condenser 7 or the like. A dial 8 is secured to the shaft 6 and provided with calibrations 9 for registry with a pointer 11 on the housing to indicate, for example, selected radio frequencies.

A lever 12 is journaled on the shaft 6 and pivotally connected at 13 to one end of an adjustable link 14 which is pivotally connected at its other end at 16 to an operating lever 17 secured on a drive shaft 18. The drive shaft 18 is journaled in bearings 19 and 21 provided on a motor support 22 secured to the housing 5. A reversible electric motor 23 is mounted on the support 22 and acts through a friction clutch 24 to drive the shaft 18.

The friction clutch 24, of conventional construction, is shown as comprising a driving plate 26 secured to the motor shaft 27, a driven plate 28 secured to the shaft 18, a friction plate 29, and a resilient member 31. The driving plate 26 and friction plate 29 are intercon-

2

nected for common rotational movement by means of a driving pin 32, and the friction plate is frictionally engaged against the driven plate 28 by means of the resilient member 31.

Rotational movement of the drive shaft 18 is limited by adjustable stop members 33 and 34 mounted on the motor support 22 for abutting engagement against opposite sides of the lever 17. The stop members 33 and 34 are shown as comprising circular disks formed with eccentric bores to receive bolts 36 and 37, respectively, extending through apertures in the motor support 22.

The dial 8 and lever 12 are locked together for common rotational movement by means of a screw 38 threaded into the lever and acting to clamp the dial rim between a pair of washers 39 mounted on the screw.

In operation, the motor 23 is energized to rotate the shaft 18 in a clockwise direction until the lever 17 moves into abutting engagement against the stop member 33. By reversing the rotation of the motor, the shaft 18 is rotated in a counter-clockwise direction until the lever 17 is moved into abutting engagement against the stop member 34. By thus rotating the shaft 18, the lever 17 acts through the link 14, lever 12, and dial 8 to position the shaft 6 in pre-selected positions. To adjust the device to obtain different shaft positions, the stop members 33 and 34 may be moved toward or away from each other and/or the dial 8 may be moved relative to the lever 12.

Having described a preferred embodiment of the present invention, it is to be understood that although specific terms and examples are employed, they are used in a generic and descriptive sense and not for purposes of limitation; the scope of the invention being set forth in the following claims.

What is claimed is:

1. An electromechanical shaft positioning device comprising a reversible electric motor, a clutch operatively connected to said electric motor, a driving lever operatively connected to said clutch for rotation in either of two directions, adjustable stop members mounted in the rotational path of said driving lever for limiting movement thereof, a driven shaft movable in either of two directions, a driven lever journaled on said driven shaft, means mounted on said driven shaft for manually rotating the same to a preset position, releasable lock means mounted on said driven lever to secure said driven shaft to said driven lever at a preset position, and a link interconnecting said driving lever and said driven lever for proportionally rotating said driven shaft in response to rotation of said electric motor.

2. An electromechanical shaft positioning device for tuning a variable radio condenser to preset positions comprising reversible electric motive means, a friction clutch operatively connected to said electric motive means, a driving lever operatively connected to said friction clutch for rotation in either of two directions, a pair of preset stop members mounted in the rotational path of said driving lever for limiting rotational movement thereof, a driven shaft operatively connected to said variable condenser and movable in either of two directions, indicating means mounted on said driven shaft, a driven lever journaled on said driven shaft, means fixed to said shaft for manually rotating the same, releasable lock means mounted on said driven lever to secure said indicating means and said driven shaft to said driven lever at a preset position of said variable condenser, and a link interconnecting said driving lever and said driven lever for proportionally rotating said indicating means, said driven shaft and said variable condenser in response to rotation of said electric motive means.
